AUXILIARY TOP FOR GAS STOVES

Filed Sept. 28, 1927

INVENTOR,
GEORGE G. GLENN.
By Martin P. Smith, Atty.

UNITED STATES PATENT OFFICE

GEORGE G. GLENN, OF LONG BEACH, CALIFORNIA

AUXILIARY TOP FOR GAS STOVES

Application filed September 28, 1927. Serial No. 222,565.

My invention relates to an auxiliary top for gas stoves, the principal object of my invention being to provide a relatively simple, inexpensive and practical device that may be conveniently used on gas stoves, gas plates and the like, and which device will be effective in utilizing heat that is otherwise wasted, and consequently effecting a material saving of gaseous fuel.

10 A further object of my invention is to provide a device of the character referred to that may be readily used on practically all gas stoves, and which device is provided with adjustable supports in order that it may be conveniently used in connection with gas plates of different heights.

With the foregoing and other objects in view, my invention consists in certain novel features of construction and arrangement of 20 parts that will hereinafter be more fully described and claimed and illustrated in the accompanying drawing, in which—

Fig. 1 is a perspective view of an auxiliary top of my improved construction.

25 Fig. 2 is a vertical longitudinal section taken on the line 2—2 of Fig. 1.

Fig. 3 is a cross section taken on line 3—3 of Fig. 1.

Fig. 4 is a view looking against the under- 30 side of an auxiliary top of my improved construction.

The auxiliary top contemplated by my invention comprises a shallow box-like structure, preferably formed of sheet metal and comprising a top plate 10, a bottom plate 11 and a side wall 12; the latter being bent in semi-circular form so as to produce a structure having rounded ends. At one end of this sheet metal housing the bottom plate 11 is cut away to provide a circular opening 13, which when the device is positioned on top of a stove or gaseous plate, occupies a position directly over one of the burners B of the stove or plate as illustrated in Fig. 2; it being understood that the top of the stove or the plate is provided with an opening 14 above said burner for the upward passage of flame and heated air from said burner.

50 The top plate 15 directly above the opening 13 is provided with a series of ribs 15,

which project slightly above the upper surface of the top plate, and said ribs serving as a support for cooking utensils that are placed on this end of the device.

Formed through that portion of the top 55 10 opposite the portion that is provided with ribs 15 is a series of openings 16, preferably slots, and the material of the top 10 is pressed upward between said slots to form ribs 17 similar to the ribs 15, and which ribs 17 serve 60 as supports for cooking utensils.

The slots or openings 16 are preferably formed so that their larger portions are disposed adjacent to the corresponding rounded end of the housing, and thus the greater portion 65 of the heated air and products of combustion will travel the full length of the housing before escaping upwardly through the slots or openings.

Arranged on the sides of the housing adjacent to the end that is provided with the openings 16 are substantially L-shaped legs 18, the vertical portions of which are provided with slots such as 19.

Seated in the side wall 12 of the housing are 70 bolts 20 that project outwardly through the slots 19, and seated on the threaded portions of said bolts are winged nuts 21.

As a result of the construction just described the legs 18 may be adjusted vertically 75 so as to properly support the housing on gas plates of different heights and when the housing is used on top of a gas stove the legs 18 may be swung into out-of-the-way positions as illustrated by dotted lines in Fig. 1.

The legs 18 are locked in their variously adjusted positions by tightening the winged nuts 21 on the bolts 20.

In the use of my improved auxiliary top in connection with one of the burners of a gas 80 plate the housing is positioned on top of the plate with the opening 13 over one of the burners of said plate and that portion of the housing that projects beyond the edge of the plate is supported by the legs 18.

A cooking utensil placed on the ribs 15 above the opening 13 is heated by the flame and products of combustion that arise from the burner B, and the heated air and products 85 of combustion that would otherwise be wasted 90 100

will pass lengthwise through the chamber within the housing and escape through the opening 16, and this heat may be utilized by placing a cooking utensil on the ribs 17 that are arranged between the openings 16, thus practically all of the heat developed by one burner is utilized and a material saving in fuel costs is effected.

By using two of the auxiliary tops in connection with a two-burner gas plate, the advantages of a four-burner plate or stove may be obtained.

Where the device is used in connection with an ordinary gas stove the housing is positioned over one of the burners, and when the same is lighted practically all of the heat developed thereby may be utilized for heating two different utensils positioned on the ribs 15 and 17.

An auxiliary top of my improved construction is comparatively simple, is inexpensive of manufacture, is effective in conserving gas used in the operation of gas stoves, gas plates and the like, and therefore effects a material saving of fuel in the operation of such stoves and plates.

It will be readily understood that minor changes in the size, form and construction of the various parts of my improved auxiliary top of gas stoves may be made and substituted for those herein shown and described without departing from the spirit of my invention, the scope of which is set forth in the appended claim.

I claim as my invention:

An auxiliary top for gas stoves and the like, comprising a housing having top and bottom plates, a continuous side wall connecting the edges of said top and bottom plates, there being an opening formed through the bottom plate at one end thereof, a series of radially disposed ribs pressed upwardly from the top plate directly above the opening in the bottom plate, there being a series of radially disposed openings formed through the end portion of the top plate opposite from the end from which the ribs are pressed which openings gradually increase in width toward the adjacent rounded end of the housing, and L-shaped supporting legs mounted on the side wall of the housing opposite the end that is provided with the bottom opening and the radially disposed ribs on the top plate, the upright members of which legs are slotted, bolts passing through the side walls of the housing and through the slots in said legs and nuts located on the threaded outer ends of said bolts for clamping the legs to said housing in differently adjusted positions.

In testimony whereof I affix my signature,
GEORGE G. GLENN.
